AGGREGATE FEED APPARATUS FOR CONCRETE BLOCK MACHINES

John E. Kovach, Nutley, N. J., assignor to Bergen Machine & Tool Co., Inc., Nutley, N. J., a corporation of New Jersey

Application February 10, 1955, Serial No. 487,437

7 Claims. (Cl. 25—103)

This invention relates to improvements in machines for making blocks, particularly concrete and cinder blocks. The invention is concerned more especially with the molds of such machines and with the apparatus for feeding aggregate from a hopper to the molds.

It is an object of the invention to provide improved means for filling the mold of a block-making machine, and for cutting off the aggregate at the right height across the top of the mold. In accordance with one feature of the invention, the aggregate is advanced from a feed hopper to the mold by means of grid plates which serve the purpose of the conventional feed drawer.

Another object of the invention is to provide an improved construction for a block-making machine at the mold box. One feature relates to the control of excess aggregate around the top edge of the mold; and another feature relates to the supporting of cores within the mold from columns which extend through the stripper head of the machine. This construction eliminates the necessity for the conventional core bar and makes it possible to charge the mold more uniformly across its full width, and makes possible the use of stripper shoes which do not have to be split to accommodate the core bar and which produce a more perfect block.

Another object of the invention is to provide apparatus for molding more uniform blocks by having vibrator mechanism within the cores. This is a particularly effective way for settling the aggregate uniformly and quickly within the molds; and with the core supporting columns of this invention, the driving mechanisms for the vibrators can extend down through hollow columns. The hollow columns provide free air to the cores so other means of venting the core is not necessary to eliminate vacuum caused during withdrawal of cores from the concrete.

Other objects, features and advantages of the invention will appear or be pointed out as the description proceeds.

In the drawing, forming a part hereof, in which like reference characters indicate corresponding parts in all the views:

Figure 1 is a diagrammatic view, mostly in section, showing the improved feeding, molding and vibrating apparatus of this invention;

Figure 2 is a diagrammatic, perspective, exploded view of a portion of the apparatus shown in Figure 1; and

Figure 3 is an enlarged, sectional view through one of the core molds showing vibrator mechanism within the core molds.

The apparatus shown in Figure 1 includes a hopper 10 for holding aggregate from which the blocks are to be molded. A plurality of grid plates 12 are connected at their upper ends to bars 14. Aggregate 15 falls down through the mouth at the bottom of the hopper 10 and into the spaces between the grid plates 12. At their lower ends, the grid plates 12 extend close to the top surface of a stationary plate 16 on which the aggregate rests, and these plates 12 serve as hoe blades for pushing the aggregate back and forth across the plate 16, as will be more fully explained in connection with the operation

2

of the apparatus. There are stationary sides 17 extending upwardly from the side edges of the plate 16 for preventing transverse displacement of aggregate located between the grid plates 12.

5 The block-making machine has a mold box 20. Within the mold box 20 there are three molds 21, best shown in Figure 2. These molds, which provide cavities into which the aggregate is charged, have side walls 23 including common walls separating adjacent mold cavities from one another. End walls 25 of the molds 21 are of the same height as the side walls 23 of the molds, and there is a top plate 27 extending away from the top edges of the molds 21 in all directions at a level flush with the plate 16 on which the aggregate rests.

10 A plain pallet 29 is held against the open bottom of the molds 21 during the time that the molds are being filled and while the aggregate is being settled in the molds. The pallet receives for bringing the pallet into position under the mold and subsequently removing it during the 15 stripping operation is not illustrated in the drawing because this mechanism is well known in the art and no showing of it is necessary for a complete understanding of this invention.

There are cores 32 located in the various molds 21. 20 There are two of these cores 32 in each of the molds shown in Figure 2; and in the front end of each mold there is an additional core 34 which provides a recess in the end face of the block. There is another end core 34 at the back end of the third mold shown in Figure 2, but 25 the other two molds make blocks which have no recess at the back end of the mold, such blocks being used for corners in cinder block walls. There might be more or less than two cores in each cavity.

The end cores 34 are rigidly secured to the end walls 30 of the molds; but the other cores 32 are supported by means which do not interfere with the molding and stripping of the blocks. In machines of the prior art, the cores corresponding to the cores 32 have been supported by bars extending lengthwise across the top of each mold. 35 These core bars have had several disadvantages. One is that the core bar is in the path of the aggregate dropping into the space between the cores and the end walls of the mold; and another disadvantage is that the core bars have been in the way of the stripper head and have required that stripper head be made with split shoes for extending down on opposite sides of the core bar. This has made the part of each block, which is under the core bar, out of reach of direct contact of the stripper shoe during a block molding operation.

40 This invention eliminates the necessity of core bars by having each core 32 connected to a column 40 which extends upwardly through an appropriate opening in a stripper head 42. Figure 2 shows these columns 40 extending through the core openings of a stripper shoe 44 at the lower end of the stripper head 42, and shows the stripper head with openings 46 through which the columns 45 extend.

45 For clearer illustration, Figure 2 shows only one stripper shoe 44 for the left-hand mold 21, but it will be understood that the stripper head 42 has similar stripper shoes 44 located over each of the other molds 21. Also for clearer illustration, only two of the cores 32 are shown attached to columns 40 extending up through the stripper head, the columns for the cores in the middle and right-hand molds being broken off.

50 The stripper head 42 reciprocates up and down with respect to the mold box in a manner well understood in the art, but the columns 42 remain at fixed levels and they are so held by a frame 50 located above the stripper head 42. This frame 50 is merely representative of some fixed support on the main frame of the block-making machine.

When the cores 32 are to be equipped with the core vibrator feature of this invention, there is a drive shaft 52 extending downwardly through each of the hollow columns 40, and there are pulleys 54 at the upper ends of the drive shafts 52. These pulleys 54 are driven by belts from a driving pulley 56 on the armature shaft of an electric motor 58 carried by the frame 50. These pulleys 54 and 56, together with the motor 58, are merely representative of power means for rotating the drive shafts 52.

Figure 3 is a diagrammatic illustration of the vibrator mechanism within one of the mold cores 32. Each column 40 is screwed into a counter bore 60 at the top of the mold core 32; and the drive shaft 52 extends downwardly through a bearing 62 within the core. The lower end of the drive shaft 52 extends into another bearing 64 in a bottom wall 65 of the core 32. On the drive shaft 52, between the bearings 62 and 64, there is an eccentric weight 67 secured to the drive shaft, and in the construction illustrated, there are thrust bearings 69 both above and below the eccentric weight 67.

When the drive shaft 52 is rotating, the eccentric weight 67 causes vibration of the core 32, and there is enough elasticity in the column 40 to permit the limited movement necessary for the vibration in directions transverse of the longitudinal axis of the column 40 and drive shaft 52. Other kinds of vibrators can be located within the core 32.

The feeding of the aggregate to the molds 21 is accomplished by advancing the plates 14 toward the left in Figure 1 so that the grid plates 12 push the aggregate across the stationary plate 16 and across the top plate 27 of the mold box and over the molds 21. The depth of the spaces between the grid plates 12 is sufficient to supply the necessary depth of aggregate for filling the molds 21 with some excess of aggregate remaining up between the grid plates 12 after the molds are filled.

There are spaces 72 between the groups of grid plates 12 to provide clearance for the supporting columns 40. As the grid plates 12 move from under the hopper 10 (Figure 1) to the left and over the mold 21, a plate 74, extending between the outside bars 14 (Figure 2), passes under the hopper mouth so that no aggregate can fall from the hopper behind the grid plates 12.

The outside bars 14 are connected by a back plate 76 extending for the full distance between the outside bars 14, and the inner bars 14 on opposite sides of the spaces 72, are connected at their back ends to the plate 76. Thus all of the grid plates 12 are supported from this plate 76.

The outside bars 14 are supported on eccentrics 78 secured to a shaft 79 which rotates in bearings at the lower ends of supporting links 80. This shaft 79 is rotated by a motor 82, indicated diagrammatically in Figure 2. The motor 82 runs continuously while the grid plates are feeding aggregate to the mold and while the grid plates are located above the mold. This rotation of the eccentrics produces an orbital movement of the bars 14 and grid plates 12. The grid plate assembly is reciprocated back and forth across the molds 21 by power applied to a shaft 84 in the directions indicated by the double arrow 85. A cam-actuated crank 86, shown in phantom in Figure 1, is a diagrammatic showing of the power means of the machine for operating the grid plates 12 on their feed stroke.

During the time that the grid plates 12 are located over the molds 21, the motor 82 agitates the grid plates 12, as previously explained, and the motor which rotates the drive shaft 52, in the columns 40, causes vibration of the mold cores 32. This agitation and vibration causes the aggregate to settle in the molds to produce a block of uniform texture and strength.

The aggregate feed assembly which includes the agitator grid plates 12 is moved back and forth by power applied to the shaft 84 in the same way as a feed drawer

is operated back and forth in conventional block making machines which use a feed drawer for conveying aggregate from a hopper to a mold box. In contrast to the usual mold charging apparatus with a single strike off bar, all of the grid plates 12 of this invention, except those farthest back, strike off excess material from above the mold as the grid plates 12 move back to position to receive a new charge of aggregate from the hopper.

When the aggregate feed has moved back to its original position under the hopper 10, the stripper head 42 descends and brings the stripper shoes 44 into contact with the blocks. It is usual to continue the vibration of the mold for a short time after the stripper shoes are in contact with the top of the block, and with the present invention this vibration includes the vibration of the cores 32 as already described. The machine can have other vibrating mechanism similar to that commonly employed for vibrating a mold, but it is not necessary with the vibrating cores of this invention since they serve to settle the material and to compact it against the sides of the mold. The vibration applied from inside the block by the cores 32 urges the aggregate outwardly against the smooth sides of the mold to produce a better block than is obtained when the sides of the mold are being vibrated.

The stripping of the block from each mold 21 is accomplished in much the same manner as with conventional plain pallet machines, except that the pressure applied to the top of the block is the pressure from a one-piece stripper shoe 44 instead of a split shoe such as is commonly used because of the core bar extending longitudinally across the top of each mold for holding the cores in place on machines of conventional construction.

In the operation of the apparatus of this invention, some quantity of aggregate, indicated in Figure 1 by the reference character 88, is often pushed across the part of the top plate 27 in front of the mold 21. In order to prevent accumulation of this aggregate, and eventual interference with the operation of the feeding apparatus, there is a frame 90 forming a fence around the upper edges of the molds 21 and some distance back from the molds along the surface of the top plate 27. This frame has sides 92 which serve as continuations of the sides 17 for preventing transverse displacement of the aggregate during the reciprocating movement of the grid plates 12, but the sides 92 of frame 90 move through a limited stroke. The entire frame 90 is pulled back by an operating crank 93 actuated by the same cam means of the machine as operate the crank 86, and at a time in the cycle when the mold is empty and a new pallet 29 has been moved into position for the next charging operation. The transverse portion of the frame 90 in front of the mold serves as a blade for pulling aggregate back to the mold. By reciprocating the frame 90 back far enough to dump the aggregate 88 into the mold, and then advancing the frame 90 to its original position, the surface of the top plate 27 is kept free of aggregate built up with successive cycles of operation.

The preferred embodiment of the invention has been illustrated and described, but changes and modifications can be made and some features can be used in different combinations without departing from the invention as defined in the claims.

What is claimed is:

1. A block-molding machine comprising a mold box, plates defining a mold cavity, a pallet closing the bottom of the mold cavity, a hopper for holding aggregate, a plate located under an opening at the bottom of the hopper, the plate being spaced from the hopper outlet, aggregate feed means comprising groups of blades extending between the level of the hopper outlet and the top of the plate which is below the hopper, the groups of blades being transversely spaced from one another to leave clearance between them for passing other struc-

ture of the block molding machine, a top plate extending from the upper edge of the mold cavity at both ends thereof and being flush with the plate that extends under the hopper outlet, operating mechanism for moving the blades back and forth between positions under the hopper outlet and positions over the mold cavity, and means for eliminating accumulation of aggregate left on the top plate beyond the mold cavity by leakage of aggregate through the space between groups of blades, said means including a blade, independent of the groups of blades, located over the top plate of the mold at the end of the mold remote from the hopper, and different motion transmitting connections that reciprocate the groups of blades through the full stroke from the hopper to the mold cavity and said blade through a shorter stroke to pull loose material from the top plate into the mold cavity before successive mold-filling strokes of the groups of blades.

2. The block-molding machine described in claim 1 and in which there are automatic timing means for operating the different parts of the machine in a controlled succession of operations and in which there are elements extending upwardly from the level of the top plate at both ends of said blade and along opposite sides of the mold cavity at a short distance outward from the mold cavity for confining excess aggregate above the mold level against transverse displacement.

3. The block-molding machine described in claim 1 and in which the groups of blades are agitated with short strokes of reciprocating movement during their travel across the mold cavity, and there are relatively fixed side walls extending along the path traversed by the groups of blades for preventing transverse displacement of the aggregate from the groups of blades during their mold-filling operation.

4. A block-molding machine including a mold box having a mold cavity therein with side walls, a pallet closing the bottom of the mold cavity, cores in the mold cavity free of the pallet and side walls of the cavity, a stripper head movable up and down with respect to the mold cavity, mold core supports connected with a fixed frame located above the stripper head, a hopper for holding aggregate, a surface located below and spaced from the hopper outlet and extending to the top edge of the mold cavity, aggregate feed means comprising groups of blades located between the hopper outlet and said surface and movable across the surface to propel aggregate to the mold cavity, the blades being spaced from one another transversely of their direction of travel so as to leave clearance for the core mold supports.

5. The block-molding machine described in claim 4 and in which the blades are located in a plurality of rows extending lengthwise of their direction of travel and opposite sides of each blade of each row are connected with

a bar extending lengthwise of the row, and there are spaces between the bars substantially equal to the width of the core supports so that the groups of blades can pass the core supports when moving forward on a feed stroke across the top of the mold cavity.

- 5 6. The block-molding machine described in claim 4 and in which the groups of blades operate between relatively fixed side walls which prevent transverse displacement of the aggregate from between the blades, common supporting means to which all of the blades are connected to form a blade assembly, and eccentric means for agitating the blades to impart a vibrating motion to them during their feeding stroke and while they are located above the mold cavity.
- 10 7. In a plain pallet block-molding machine having a mold with side walls and a pallet closing the bottom of the mold, a surface extending substantially horizontally from the top of the mold and under an outlet of an aggregate hopper, side walls extending along said surface to prevent transverse displacement of aggregate from the surface, cores within the mold free of the pallet and side walls of the mold, a frame located above the level of the top of the mold, supports for the cores extending upwardly therefrom and connected to the frame, a plurality of hoe blades that move back and forth across said surface from positions under the hopper to positions over the mold, the hoe blades being at a level below said frame and different hoe blades being on different sides of the core supports when the hoe blades are in advanced positions over the mold, vibrator means in the mold cores for vibrating the cores independently of the mold, power means extending downwardly through the core supports for driving the vibrator means in the cores, and other power vibrating means connected with the hoe blades for agitating the aggregate before it drops into the mold.
